UNITED STATES PATENT OFFICE

100,484

DESIGN FOR A REFRIGERATOR CABINET OR SIMILAR ARTICLE

John Milton Van Patter, Aylmer, Ontario,
Canada

Application May 16, 1936, Serial No. 62,685

Term of patent 3½ years

To all whom it may concern:

Be it known that I, John M. Van Patter, a citizen of Canada, residing at Aylmer, in the Province of Ontario and Dominion of Canada, have invented a new, original, and ornamental Design for a Refrigerator Cabinet or Similar Article, of which the following is a specification, reference being had to the accompanying drawing, forming part thereof.

The figure is a view in perspective of a refrigerator cabinet or similar article embodying my design.

I claim:—

The ornamental design for a refrigerator cabinet or similar article, as shown.

JOHN MILTON VAN PATTER.
